UNITED STATES PATENT OFFICE.

ERIC S. SWANSTROM, OF BROOKLYN, NEW YORK.

SPINNING-TOP.

1,206,942.

Specification of Letters Patent. Patented Dec. 5, 1916.

Application filed September 12, 1916. Serial No. 119,660.

To all whom it may concern:

Be it known that I, ERIC S. SWANSTROM, a citizen of the United States, residing at Brooklyn, in the county of Kings and State 5 of New York, have invented certain new and useful Improvements in Spinning-Tops; and I do hereby declare the following to be a full, clear, and exact description of the invention, such as will enable others 10 skilled in the art to which it appertains to make and use the same.

This invention relates to new and useful improvements in a spinning top and one of its objects is the provision of a device of 15 this character, which shall be simple, durable and efficient, and which may be manufactured and sold at a comparatively low cost.

Another object of this invention is to provide screw threads upon the conical portion 20 of the top extending from the pindle and terminating adjacent the flange upon the top, whereby the flange will grip the cord at a point where the cord leaves the threads 25 to prevent the cord from slipping or becoming loose upon the top.

With these and other objects in view as will become more apparent as the description proceeds, the invention consists in certain 30 novel features of construction, combination and arrangement of parts as will be hereinafter more fully described and claimed.

For a complete understanding of my invention, reference is to be had to the following 35 description and accompanying drawing, in which:—

Figure 1 is a side elevation of a spinning top, constructed in accordance with my invention, and Fig. 2 is a similar view illustrating a cord applied to the screw threads 40 of the top.

Referring in detail to the drawing, the numeral 1 indicates as an entirety, a spinning top, consisting of a conical-shaped portion 2 having secured to one end thereof in any suitable manner the usual pindle or plug 3. Formed upon the upper end of the conical portion 2 is a flange 4 having a bevelled face 5.

The conical-shaped portion 2 has formed thereon screw threads 6 which extend from the pindle or plug 3 in the direction of the flange 4 and terminate adjacent thereto, 55 whereby when a cord 7 is wound upon the threads 6 from the pindle or plug 3 in the

direction of the flange 4, the upper run of the cord when leaving the upper run of the screw threads will bind against the bevelled face 5 of the flange 4 and be prevented from accidentally slipping from the screw threads or becoming loose thereon.

If desired a rod 8 constructed of any suitable material and preferably of wood is secured to one end of the cord 7, whereby a child or person may grip the handle end of the rod 8 after the cord 7 has been wound upon the conical portion 2 and by giving the rod 8 a whipping action, the top 1 will be spun upon the pindle or plug 3 by the action of the cord 7 being drawn from around the screw threads 6.

From the foregoing description taken in connection with the accompanying drawing, it will be noted that a spinning top has been provided which may be efficiently and easily operated by a child and also means being provided whereby the cord will be held from unwinding from the top previous to being spun.

While I have shown and described the preferred embodiment of my invention, it will be understood that minor changes in construction, combination and arrangement of parts may be made without departing 85 from the spirit and scope of the invention as claimed.

Having thus described my invention, what I claim is:—

1. A spinning top comprising a conical-shaped portion, a pindle secured to said conical-shaped portion, screw threads formed on the conical-shaped portion for receiving a cord, and means formed on the conical-shaped portion for coöperation with the screw threads for gripping the cord to prevent it from unwinding.

2. A spinning top comprising a conical-shaped portion, a pindle secured to said conical-shaped portion, screw threads formed on said conical-shaped portion, and a flange formed on the upper end of the conical-shaped portion and having a bevelled face for coöperation with the upper run of the screw threads to prevent a cord from slipping from the screw threads.

In testimony whereof I affix my signature in presence of two witnesses.

ERIC S. SWANSTROM.
